ABSTRACT OF THE DISCLOSURE

The seals of high current carrying capacity incandescent lamps are described. A refractory metal cup is encapsulated in a glass jacket and the top of the jacket is fused to a quartz sleeve, which is then fused to a quartz disc. The latter is then sealed to a lamp envelope. The base of the cup has apertures through which electrical conductors are disposed. At one end, the conductor extends outside of the lamp and at the other end to a filament. The lamp seal and the current-carrying path are thereby separated from each other.

This application is a division of our copending application Ser. No. 596,908, filed Nov. 25, 1966, now abandoned.

This invention relates to lamps having tungsten filaments enclosed in sealed envelopes, the latter being of fused quartz or other suitable glass. Such devices generally contain a halogen, such as iodine or bromine, and are usually called halogen quartz lamps. They operate on a regenerative cycle, initiated when a tungsten halide is produced and chemically combines with the particles evaporated from the incandescent tungsten filament. Subsequent thermal decomposition of this compound replaces the tungsten particles on the filament. More particularly, this invention concerns an improved method of sealing quartz lamps adapted to be operational with high current loadings of the type described above.

Such high current lamps have many uses especially in the fields of motion pictures, television, photography and infrared heating. In these industries, an ever-increasing demand for more illumination has burdened the lamp manufacturer with added design problems. To appreciate these problems, it must be recognized that in the past, when the wattage of a lamp was increased, the lamp envelope usually also increased in size. In the fields mentioned above, the demand for higher wattage lamps increased to a point where thousands of watts were required. Therefore lamp envelope size became a burden to both lamp and fixture designers.

The lamp industry overcame this problem of increased lamp size by using quartz envelopes and halogen fills so that wattage could be increased while using smaller envelopes. However, with lamps of larger wattages a more perplexing problem was encountered in the fabrication of the seal.

Briefly, in the fabrication of quartz-halogen lamps of relatively low wattage, the important sealing operation includes using wafer-thin strips of molybdenum as current conductors in the seal area. These strips were welded between a lead-in wire and a filament-support wire. This assembly was fitted into a quartz tubular envelope and after heating of the quartz, a mechanical sealing die was brought into operation. This sealing operation pinched the area where the molybdenum strip bridged the lead-in wires and provided a vacuum-tight seal. Normally, on all standard low wattage lamps, this sealing operation was adequate. But with the ever-increasing need for high watt-

2

age; the molybdenum foil strips could not wholly fulfill the need.

The problems encountered with the use of molybdenum foil as a seal conductor in high wattage lamps are many, but the most critical points are:

(A) The use of molybdenum foil in glass-to-metal seals requires the foil to be thin enough to be stretched by tensile stresses, but insufficient to break the glass seal, yet not so thin that the foil itself is fractured. Molybdenum strips as thin as 0.01 mm. are likely to be fractured by tensile stress if the width exceeds 2 mm. Therefore a wider strip would have to be made from thicker material, which in turn proved too heavy for trouble-free sealing from lamp-to-lamp.

(B) The production of this foil, such as molybdenum, by mechanical methods is also very difficult, so a more expensive method using an acid or electrolytic etching process is necessary to reduce the thickness of the foil to its final dimensions.

(C) Because of the small cross-section of the foil, the current-carrying capacity is limited to about ten amps. Therefore, in fabrication of high current lamps, it is necessary to try to utilize a multiplicity of strips for current-carrying.

(D) The fragile make-up of the foil made welding to other current lead wires a critical operation.

(E) Added problems were also encountered when current was passed through a multiple foil seal. Due to the low thermal conductivity of quartz glass, a continuous heat build-up in the foil caused a voltage drop across the seal. For example, a voltage drop of as much as 1.5 volts in a 21W-150W iodine-quartz lamp was noticed. Due to this change, a higher voltage was needed to give the required light output. Most filaments are designed to operate at their maximum electrical capacity and therefore it was necessary to process them to withstand the added surges of starting voltages.

Accordingly, an object of our invention is to separate the seal from the current-carrying path of the filament of the lamp.

Another object of our invention is to simplify the sealing of high wattage lamps.

A further object of our invention is to strengthen the lamp construction.

An advantage of our invention is that it permits the use of extremely high current through a quartz-to-metal seal, thus greatly extending the range of lamp sizes.

The various figures of the drawings are the schematic view in the nature of a flow sheet depicting the various fabrication steps taken in our present invention.

In FIG. 1 a tapered conductor cup is shown in cross-section showing in particular the taper and the centrally located hole.

FIG. 2 shows the tapered conductor cup completely sealed in glass.

FIG. 3 shows the encapsulated cup affixed to a glass tubular member showing the outer glass removed midway of the tapered cup.

FIG. 4 shows two assemblies as described in FIG. 3 in position to be affixed to a glass disc.

FIG. 5 shows the completed assembly of the tapered cups and glass disc.

FIG. 6 shows a filament assembly positioned and welded to the tapered cup.

FIG. 7 shows a glass envelope sealed to the glass disc assembly with clamp legs fitted over the end wires and having an exhaust tube positioned for final sealing of lamp.

FIG. 8 shows a complete lamp assembly.

In each of the figures of the drawing similar numerical designations are indicative of similar elements of structures.

In our present invention, we utilize a molybdenum cup as a sealing enclosure. In this way, the edges of the cup form a seal with a quartz envelope. The base of the cup is provided with a centrally located aperture for the provision of a filament-supporting conducting rod that is brazed or half-arc welded in place. This provides an unrestricted current-carrying path to the filament of the lamp. With this novel arrangement, the problems encountered with current-carrying conductor seals are eliminated.

Referring to FIG. 1 of the drawings, a tubular cup 10, made preferably from molybdenum or similar metal, is shown in cross-section. The tubular cup 10 is constructed from material of about 0.010 in thickness, tapering from its base 12 to a feather edge 14 of about 0.002 in thickness. The central portion of the base of the cup is provided with an orifice 16. Cup 10 is the basic component of the seal portion of the lamp assembly. The feathered edge of the cup 10 will be sealed to the lamp and the orifice 16 will hold an electrical lead as will be further described.

In FIG. 2 the first step in the assembly of the lamp is encapsulating the cup 10 with a jacket 18 of fused quartz or other suitable glass. As viewed in FIG. 2 the cup is completely enclosed within a glass jacket 18 having an appended exhaust tube 20 affixed thereto. A support portion of the exterior part of the jacket 18 is then cut from the cup 10. This leaves the lower half portion of the cup 10 exposed as viewed in FIG. 3. The inner wall of the cup 10 and the top part of the orifice 16 still retain the glass jacket 18. Still referring to FIG. 3, a similar diameter tubular quartz sleeve 22 is then fused to the mouth of the jacket portion 18, thereby adding a section of glass approximately equal in length to that of the top glass jacket. With this operation completed, a finished subassembly 24 is realized. As viewed in FIG. 4, two similar subassemblies 24 can be seen prior to their attachment to a quartz disc 26 in a conventional glass fusing operation to provide a base assembly 23.

The quartz disc 26 as viewed in FIG. 4 is provided with a pair of spaced-apart orifices. To fabricate the lamp base 28 the end of the sleeves 22 are fitted into the orifices where a fusing operation joins the sleeve to the quartz disc 26.

A completed cross-section of the above described base assembly arrangement 28 can be viewed in FIG. 5 which shows the complete glass-covered interior wall. This assembly 28 is then ready to receive a filament structure 30, comprising a suitable coiled-coiled tungsten filament 32. Filament 32 is supported equidistantly between a pair of parallel tungsten rods 38 by a pair of short spuds 34 welded to the top of the tungsten rods 38 and penetrating several turns of the end portions of the coiled-coiled filament. The tungsten filament support rods 38 are of different lengths as viewed in FIG. 6, one terminating at the base of the filament and the other at its top. The rods 38 in conjunction with the short spuds 34 axially support the filament in relation to the base assembly 28.

An ultrasonic drill is then utilized to clear the orifices of the glass coating so that the filament assembly 30 can be fitted through the orifices 16 in the cups 10. The rods

38 are extended beyond the ends of the bases of the cups 10 to a desired length. A weld 40 is then applied to the rods 38 and the base 12 of cups 10 at the orifice 16.

As viewed in FIG. 6, the filament structure 30 is shown secured to the base assembly 28. The filament structure 30 is then covered by a suitable quartz envelope 42 having an appended exhaust tube 44 affixed thereto. The envelope 42 is heated in the vicinity of the disc 26 thereby fusing the envelope 42 to the base assembly 28.

The lamp structure 46, as viewed in FIG. 7, is tipped at the exhaust tube 44 after a series of exhausting and filling operations where a predetermined amount of halogen is added under the required conditions.

As viewed in FIG. 8, a completed lamp structure 46 is shown. After the filling and tipping operation of the lamp envelope a final step is initiated. A pair of metal end clamps 50 are fitted over each of the metal end cups 10 and rod ends 38. The clamps 50 are secured in place by suitable set screws 52 that are tightened against the rod ends 38. This final step provides the lamp structure 46 with a uniform bi-prong base to conform with the existing fixtures in industry.

While there has been shown and described what is at present considered the preferred embodiment of the invention, it will be obvious to those skilled in the art that various changes and modifications may be made therein without departing from the spirit and scope of the invention as defined by the appended claims.

As our invention, we claim:

1. A process of sealing the ends of incandescent lamps having a tubular metal cup at an end thereof and having a filament supported in a centrally located orifice in the base thereof the steps which comprise: encapsulating said cup in quartz glass; removing the lower exterior portion of said glass to expose the base of said metal cup; fusing a tubular quartz sleeve to the mouth of said cup; fusing said sleeve to a quartz disc; removing a portion of the quartz glass disposed near said orifice; passing a rod adapted to support a filament through said orifice into said cup; securing said rod to said cup at a point where it passes through said orifice; placing a quartz envelope about said rod; fusing said envelope to said disc; exhausting said lamp envelope and filling it with a suitable gas filling.

2. The process according to claim 1 wherein the width of the sides of the cup tapers to a feathered edge from the base.

3. The process according to claim 1 wherein there are two orifices disposed in said quartz disc and each have a quartz envelope and cup disposed thereon.

4. The process according to claim 1 wherein said cup and said rod are each formed of a refractory metal.

5. The process according to claim 4 wherein said cup is formed of molybdenum and said rod is formed of tungsten.
